UNITED STATES PATENT OFFICE.

RUSSELL V. JUDSON, OF DETROIT, MICHIGAN.

COMBINED POLISHING AND SORTING MACHINE.

Application filed November 30, 1928. Serial No. 151,744.

This invention relates to machines designed for automatically sorting or "picking" grain, such as beans, by utilizing the differences in smoothness of surface and 5 regularity of outline which usually distinguish the perfect or better quality kernels from those which are split, rotted, shriveled or otherwise below grade. Since any dirt adhering to the surface of the grain will 10 tend to increase its roughness and thereby cause such a machine to discard such dirt-roughened kernels regardless of their actual quality, the object of this invention is to provide means for removing the dirt and 15 polishing the grain prior to the sorting operation, preferably as a step in a continuous process of treatment and by means incorporated in the same machine which does the sorting. It consists in certain elements and 20 features of construction in combination as herein shown and described, and as indicated by the claims.

In the drawings:

Figure 1 is a perspective view of a machine embodying this invention, partly in section and with certain parts broken away to show details of construction.

Figure 2 is a bottom plan view of a polishing brush for the machine.

Figure 3 is a detail section taken at a radial vertical plane through the polishing brush and associated parts.

For purposes of illustration I have shown this invention applied to a machine which 35 is generally similar to that shown in my co-pending application Serial No. 630,667, entitled Centrifugal sorting machine, but it may be understood that the utility of the invention is not confined to this particular 40 model or even to this particular type of structure, though as to certain features it is especially well adapted for incorporation in a machine of the centrifugal class.

Referring first to Figure 1, the supporting 45 base or pedestal, 1, extends upward in the form of a hollow center post, 2, which carries an annular bearing, 3, on which there is revolvably mounted a frame, 4, supporting a series of radially disposed rubber rolls, 5, 50 whose function is to separate the rough kernels from the smooth ones by frictional engagement with the former and by permitting the latter to travel radially outward under the influence of the centrifugal force generated by revolution of the frame, 4. An up-standing flange or wall, 6, on the frame, 4,

forms an annular trough, 7, from which the beans are distributed through ports, 8, leading to the several pairs of picking rolls, 5. A feed hopper, 9, into which the beans are initially placed is preferably provided with a coarse mesh screen, 10, to hold back any large stones or other impurities, and from the discharge throat, 11, of the hopper, 9, the beans flow by gravity onto a screen, 12, of finer mesh which allows the passage of only the fine dirt or scale. A funnel, 13, directly below the screen, 12, collects this dirt and discharges it downwardly through the hollow post, 2.

For polishing the beans prior to their delivery to the sorting rolls, 5, I provide a brush member, 14, which is supported over the screen, 12, by brackets, 15, up-standing from the base of the trough, 7, and secured rigidly thereto so that the brush, 14, is revolvably with the frame, 4, while the screen, 12, being supported on the funnel, 13, and post, 2, is stationary. The bristles, 16, of the brush, 14, extend closely adjacent the screen, 12, being spaced above it only enough to permit the passage of the beans under the brush and in contact with the ends of the bristles so as to receive a polishing action therefrom as they travel outwardly toward the edge of the screen, 12, to fall into the trough, 7, for distribution to the picking rolls, 5. To insure such outward movement of the beans over the screen, 12, I find it preferable to arrange the bristles, 16, in spiral rows as shown in Figure 2, and in such relation to the direction of rotation as I have indicated by the arrow, A, on said Figure 2. Thus in their passage across the screen, 12, the beans are quite thoroughly scoured and tumbled so that the sound and smooth kernels have all dirt loosened and removed from their surfaces so as to insure that they will pass freely across the picking rolls. This also gives them a polish which 90 renders them more attractive and salable than otherwise.

The center of the brush board, 14, is formed with an opening, 17, affording ample clearance around the discharge throat, 11, of the fixed hopper, 9. As the good beans are discharged centrifugally from the rolls, 5, they fall into the outer collecting funnel, 18, which is fixedly supported on the base and whose discharge spout, 19, may be arranged over a trough, 20, leading directly to a bag, 21, which is to be filled with the selected 105 110

grain. An inner funnel, 22, collects the "culls" and dirt which are pulled through the rolls, 5, by frictional contact, and this material is discharged by a spout, not visible in the particular view of the machine afforded by the drawing. The dirt which is eliminated by the screen, 12, passes directly downward through the hollow post, 2, into a bin or box, 23, as indicated. The collecting hoppers, 18 and 22 are stationary, and motion is transmitted to the revoluble frame, 4, from a pulley, 24, on a shaft, 25, extending through the hoppers and fitted at its inner end with a bevel gear, 26, meshing with suitably formed gear teeth, 27, on the under side of the member, 4. In order to make a portable unit of the entire machine, the feed hopper, 9, may be rigidly carried by means of supports, 28, extending upwardly from the rim of the hopper, 18.

I claim:—

1. In a grain sorting machine which includes a receiving hopper and sorting mechanism to which the grain is fed therefrom, a polishing device interposed between the hopper and said mechanism comprising a support and a brush movable with respect to each other and between which said grain is passed; such relative movement being derived from the movement of the sorting mechanism.
2. In a grain sorting machine which includes a receiving hopper and sorting mechanism to which the grain is fed therefrom, a polishing device incorporated in said machine and comprising a support for the grain and a brush adjacent said support, the grain being caused to pass between said brush and support on its way from the hopper to the sorting mechanism.
3. In the combination defined in claim 2, said grain being advanced between the brush

and support by movement derived from the movement of the sorting mechanism.

4. In combination with a centrifugal grain sorting machine comprising a revoluble frame supporting radially disposed picking rolls and an annular trough into which the grain is fed for distribution to said rolls, a hopper centrally mounted with respect to said trough, a dirt screen onto which the grain is discharged from said hopper and over which it moves to said trough, and a brush disposed over said screen for polishing engagement with the grain as it moves toward the trough.

5. In the combination defined in claim 4, the screen being fixedly mounted and the brush being operatively connected with the said frame to revolve therewith.

6. In the combination defined in claim 4, a center post upon which the revoluble frame is journaled, a dirt collecting funnel supported on said post and serving to support the screen in fixed relation thereto; the brush being attached to said frame to revolve with it.

7. In the combination defined in claim 4, a hollow center post upon which the revoluble frame is journaled, a dirt collecting funnel supported on said post and discharging therethrough with the screen supported on said funnel in fixed position; the brush being operatively connected with the frame for revolution over said screen.

8. In the combination defined in claim 1, the grain being fed onto the support at a central point, and the brush comprising bristles arranged in spiral formation with respect to such point for causing the grain to move outwardly therefrom over the support.

RUSSELL V. JUDSON.
